(57) CLAIM

A combination bonnet with eye mask, as shown and described.

DESCRIPTION

FIG. 1 is a front perspective view of a combination bonnet with eye mask covering the eyes showing my new design; FIG. 2 is a front view thereof; FIG. 3 is a back view thereof; FIG. 4 is a left side view thereof; FIG. 5 is a top view thereof; FIG. 6 is a bottom view thereof; FIG. 7 is a front view with the eye cover not covering the person's eyes; and, FIG. 8 is a left side thereof. The broken lines showing a human head depict environment and form no part of the claim.
